UNITED STATES PATENT OFFICE.

JOHN J. DOYLE, OF CHICAGO, ILLINOIS, ASSIGNOR TO THE SCHOLIHORN & TIESING MANUFACTURING COMPANY, OF NEW HAVEN, CONNECTICUT.

FLAP FOR CARRIAGE-DOORS.

SPECIFICATION forming part of Letters Patent No. 285,240, dated September 18, 1883.

Application filed July 5, 1883. (No model.)

To all whom it may concern:

Be it known that I, JOHN J. DOYLE, of Chicago, in the county of Cook and State of Illinois, have invented a new Improvement in 5 Flaps for Landau-Carriage Doors; and I do hereby declare the following, when taken in connection with accompanying drawings and the letters of reference marked thereon, to be a full, clear, and exact description of the same, 10 and which said drawings constitute part of this specification, and represent, in—

Figure 1, a perspective view of the flap in its raised position; Fig. 2, a side view showing it as applied to the door of a carriage; 15 Fig. 3, an end view looking toward the hinge, in the position as when the flap is turned down. Fig. 4, a central section showing the flap turned down, broken lines indicating the flap in its raised position.

20 This invention relates to an improvement in that part of a landau-carriage called the "flap"—that is to say, the hinged guide which is attached at each side of the door to support the glass when raised; but when the glass is 25 dropped the flap is turned down upon the top of the door, so as to cover the pocket.

In the usual construction, the hinge of this flap, when turned down, leaves an opening at 30 the joint, which not only gives an unfinished appearance to that part of the carriage, but offers a receptacle for dirt, which produces an obstruction to the proper working of the flap.

The object of my invention is to construct 35 the joint of the flap so that no opening will appear; and it consists in the construction as hereinafter described, and more particularly recited in the claim.

40 A is the stationary part of the flap, which is screwed upon the door-pillar; B, an arm, which extends therefrom so as to be screwed down onto the top of the door. The flap C is of usual shape except as to the hinge. The stationary piece A is constructed with a 45 knuckle, D, upon the upper end. The corre-

sponding end of the flap is recessed to receive 45 the said knuckle, the recess extending between the two flanges *a a* of the flap. The knuckle is substantially cylindrical in shape, and the recess is made in a semi-cylindrical projection, E, on the end of the flap. The pintle of the hinge passes through the ears *a a* and the knuckle, so that the knuckle stands within the cylindrical projection E and is inclosed by it. The knuckle D overhangs, so as to bring the stop for the flap when turned up 50 upon the under side, beneath the pintle, as at *d*. (See Fig. 4.) The semi-cylindrical projection E extends over the knuckle, and so as to strike below the knuckle, as at *d*, when it reaches its perpendicular position. It is by 55 making this semi-cylindrical projection to cover the knuckle and bringing the stop below and beneath that I am enabled to conceal the joint, the stop heretofore having been made at a position above and whereby the turning 60 down of the flap necessarily uncovered the knuckle. The pillar is recessed as at F, Fig. 2, so that this projection E will enter therein when the flap is closed, and then when turned 65 down, as in broken lines, Fig. 2, the projection 70 E will cover the knuckle.

I claim—

The herein-described improvement in flaps for landau-carriage doors, consisting in the part A, constructed for attachment to the 75 door-pillar, and with a knuckle, D, at its upper end, constructed to form the stop *d* beneath the pintle, combined with a flap, C, constructed with a semi-cylindrical projection, E, having a recess to inclose the said knuckle to which 80 the said flap is hinged, and so as to strike the stop *d* beneath the pintle when the flap is turned up, substantially as described.

JOHN J. DOYLE.
